UNITED STATES PATENT OFFICE.

PALEMON H. GASKINS, OF JACKSONVILLE, FLORIDA.

LUBRICATING SYSTEM.

Original application filed January 10, 1921, Serial No. 436,207. Divided and this application filed October 6, 1921. Serial No. 505,821.

To all whom it may concern:

Be it known that I, PALEMON H. GASKINS, a citizen of the United States, and a resident of Jacksonville, in the county of Duval and 5 State of Florida, have invented certain new and useful Improvements in Lubricating Systems, of which the following is a specification.

My invention relates in general to lubricating systems and more particularly to a lubricating system for the shackle connections and springs of vehicle spring suspensions such as shown in my co-pending application for lubricating systems, filed January 15, 1921, Serial No. 436,207, of which this application is a division.

The object of my invention is to provide a lubricating system of this character which maintains a film of oil or other lubricant between all of the relatively movable parts of the shackle connection and which utilizes the excess oil from the shackle connection to lubricate the spring, the excess oil being taken up and distributed over the spring so 25 as to find its way in between the leaves thereof, thereby reducing wear, eliminating noise and insuring even, smooth and efficient action of the spring suspension.

Another object is to provide a lubricating system of this character which is of extremely simple and durable construction, reliable in operation, readily organized with the elements of the conventional spring suspension, and easy and inexpensive to manufacture and maintain.

Other objects and advantages of the invention reside in certain novel features of construction, combination and arrangement of parts, which will be hereinafter more 40 fully described and particularly pointed out in the appended claims, reference being had to the accompanying drawings forming part of this specification, and in which:

Figure 1 is a fragmentary view in longitudinal vertical section through an embodiment of the invention, parts being shown in elevation for the sake of illustration; and

Figure 2 is a view in transverse vertical section, on line 2—2 of Figure 1.

50 Referring to the drawings wherein for the sake of illustration is shown the preferred embodiment of the invention, the character C designates generally a side member of a chassis of a vehicle which comprises 55 a channeled construction including a body

portion c and side flanges c' and c''. A spring suspension including a leaf spring L is associated with the chassis, one end of the leaf spring being pivotally secured to the side member C of the chassis by a shackle connection designated generally at S.

The shackle connection S includes an upper shackle bolt 10 extending through suitable openings provided therefor in the side flanges c' and c'' of the side member of 65 the chassis and a lower shackle bolt 11 extending through the eye L' of the leaf spring. Hangers or links 12 and 13 are pivotally connected at their ends to the shackle bolts, the link 12 being confined between the heads of the shackle bolts and the chassis and spring and the link 13 being maintained in proper position on the shackle bolts by means of nuts 14 and 15 threaded on the shackle bolts 10 and 11. Washers 16 and 17 70 are preferably interposed between the nuts 14 and 15 and the adjacent portions of the link 13. A bushing 19 is mounted on the lower shackle bolt 12 between the shackle bolt and the eye L' of the leaf spring L. 80

The shackle bolts 10 and 11 are of identical construction and are each provided with axial bores, designated at 10^a and 11^a, respectively, radial bores 10^b and 11^b communicating with said axial bores and disposed approximately centrally of the shackle bolts and peripheral grooves 10^c and 11^c communicating with the radial bores 10^b and 11^b, respectively.

Means is provided for supplying lubricant 90 to said shackle bolts and includes a bushing 20 mounted on the portion of the upper shackle bolt 10 comprehended between the side flanges c' and c'' and a lubricant supply pipe 21 arranged in the channel of the chassis and conveying a supply of lubricant under pressure from a reservoir or other suitable source of supply. A branch 22 extends from the supply pipe 21 through the bushing 20 and communicates with the peripheral groove 10^c of the upper shackle bolt.

A pipe connection 24 has one end offset and threaded into the axial bore 10^a of the upper shackle bolt 10 and its other end 105 similarly offset and threaded into the axial bore 11^a of the lower shackle bolt 11. The pipe connection 24 affords a free and unobstructed conduit through which the lubricant may flow directly from the axial bore 11^a.

of the upper shackle bolt 10 into the axial bore of the lower shackle bolt 11.

The excess oil from the shackle connection is utilized to lubricate the leaf spring 5 L, and for this purpose an envelope of absorbent material, designated at 25 encases the leaf spring and extends around the shackle connection. The envelope of absorbent material takes up the excess oil 10 from the shackle connection and distributes it over the entire surface of the leaf spring so that it finds its way in between the leaves thereof. A boot or casing 26 of flexible and 15 impervious material encases the envelope and serves to confine the lubricant to the envelope. The boot 36 is split to permit assembly on the spring and the meeting ends of the split are provided with a lacing device 27 or other suitable fastening means for 20 securing said meeting ends together. Adjacent the shackle connection, the boot is provided with a removable section 28 slotted, as at 29, to accommodate the hangers of the shackle connection and releasably secured in position by means of snap fasteners 25 30. The boot is also slotted as at 31 to accommodate the projecting end of the lower shackle bolt.

In operation, the lubricant flows through 30 the supply pipe 21 under pressure and from the branch 22 thereof is fed into the peripheral groove 10^a of the upper shackle bolt 10. From the peripheral groove 10^a a part of the lubricant is distributed over the 35 surface of the upper shackle bolt and over the contacting surfaces of adjacent relatively movable parts and the remainder of the lubricant flows through the radial bore 10^b, axial bore 10^c and pipe connection 24 into the axial bore 11^a of the lower shackle bolt 40 and thence through the radial bore 11^b thereof into the peripheral groove 11^c from whence it is distributed over the contacting 45 surfaces of the adjacent relatively movable parts.

The excess oil from the shackle connection is taken up or absorbed by the wicking or absorbent material 25 and discharged therethrough and consequently over the entire area of the leaf spring, and from the 50 wicking finds its way in between the leaves

of the spring. The lubricant is confined by the casing 26 to the wicking and the spring and at the same time as both the wicking and the casing are flexible they in nowise interfere with the flexion or other action of the spring. The casing and wicking are easily assembled on the spring and when once assembled need no further attention.

In this manner a film of oil is obtained 60 between all of the movable parts of the spring suspension, thus greatly reducing wear, eliminating noises and insuring smooth, even and efficient action.

I claim:

1. In a lubricating system, in combination, a chassis including a channel side member, a spring, a shackle connection between the chassis and the spring, including a shackle bolt having passages for the lubricant, means 70 for supplying lubricant to said shackle bolts including a supply pipe extending through the channel member of the chassis and communicating with the passages of one of the shackle bolts, a pipe connection between the 75 passages of the shackle bolts for conveying the lubricant supplied to the passages of one of the shackle bolts by the supply pipe to the passages of the other of said shackle bolts, and means for utilizing the excess lubricant 80 from the shackle connection to lubricate the spring and including an envelope of absorbent material encasing the spring and associated with the shackle connection and a boot of flexible impervious material encasing 85 the absorbent envelope.

2. In a lubricating system, in combination, a chassis, a spring, a shackle connection between the chassis and spring including upper and lower shackle bolts, means for supplying lubricant to the upper shackle bolt, means for lubricating the lower shackle bolt from the upper shackle bolt, and means for utilizing the excess lubricant 90 from the shackle connection to lubricate the 95 spring and comprising an envelope of absorbent material encasing the spring and associated with the shackle connection, and a boot of flexible impervious material encasing said absorbent envelope.

PALEMON H. GASKINS.
